UNITED STATES PATENT OFFICE.

JOHN COMERMA, OF NEW YORK, N. Y., ASSIGNOR TO BESSIE D. KENNEDY, OF LARCHMONT, NEW YORK.

FIREPROOF WALL BOARD.

Application filed September 22, 1921. Serial No. 502,373.

To all whom it may concern:

Be it known that I, JOHN COMERMA, a subject of the King of Spain, and resident of New York, in the county of New York and 5 State of New York, have invented certain new and useful Improvements in Fireproof Wall Board, of which the following is a specification.

The invention relates to the construction 10 material known as "fireproof wall board," that is to say, an artificial board made up of material such as plaster of Paris surrounded by a fibrous covering material as a heavy cardboard or the like.

15 The invention has for its object to provide a board of this character in which a continuous covering is arranged over the front and both side edges and in which the seam or seams formed on the back will be 20 adequately reinforced to prevent the same from opening. To this end, there is secured by the plaster a strip or strips of, for example, material similar to that of the covering, the same extending in both directions 25 over a seam and in the one direction, preferably, also to the corresponding edge of the board.

The nature of the invention, however, will 30 best be understood when described in connection with the accompanying drawings, in which—

Fig. 1 is a transverse section thru a length 35 of board.

Figs. 2 to 4 are similar views illustrating 40 modifications.

Similar characters of reference designate 45 corresponding parts thruout the several views.

Referring to the drawings, 10 designates 50 the body material, such as plaster of Paris, which is applied in plastic condition in manner well understood in the art. The plaster is designed to be held between the covering material 11 which may consist of sheets 55 of material as cardboard or the equivalent and is brought over the both side edges, as shown, to make a continuous and unbroken front and side portions. The edges may be brought together; but it is preferred to introduce an intermediate strip 12 between 60 same and running lengthwise of the board over the back thereof.

Two seams 13 result; and it is the object 65 of the invention to prevent the same from opening while allowing of the simple man-

ner aforesaid of applying the covering 11, which at the same time affords suitably protected edges. The portion of the board in proximity to the longitudinal seams 13 is, for this purpose, reinforced by a further 60 longitudinal strip or strips 14 of suitable material as cardboard or material similar to the covering 11, the same being arranged to extend for an appreciable distance upon either side of a seam, for example within 65 the body material 10, as shown in Fig. 1, and in proximity to the bounding material of the back. Or, the bounding material may be displaced inwardly for a distance from the edges, as shown in Fig. 2, and the 70 reinforcing strip 14 located on the outside thereof and flush with the back surface.

Further modifications in the mounting of a strip 14 are illustrated in Figs. 3 and 4 where a portion of the reinforcing strip 14 75 is located within and the remainder without the bounding material, passing thru the seam thereof, Fig. 4, showing the mounting in the reverse position from that shown in Fig. 3.

It is preferred, also, to reduce the cross-section of the board for a short distance 80 inwardly along the sides, so that an overlapping by plaster finishing material at the joints of successive sheets may be effected. 85 The covering material 11 assists the securing of the sheets in affording nail holding material of a fibrous nature. In this connection, the corresponding portion of a strip 14 is directed toward the reduced section so 90 as to extend therein substantially to the side edge and thus provide additional nail holding material and at the same time serve also to reinforce the portion of reduced 95 cross-section. It will be appreciated that the fibrous material of the back of the board is the portion taking the tension stresses and that by the use of the strip 14 additional tensile strength is afforded the back, particularly at the portion of reduced cross-section. The strip 14, moreover, securely 100 binds the two separated cover portions together in a very substantial manner by reason of the large cohesive surface provided.

Furthermore, bringing the covering material over both of the side edges allows of the more simple manufacture of the board and thru the use of the back strip 12 between the edges of the covering, the registry 110

of the covering material and back strip need not be so accurately effected as the reinforcing strips 14 will serve to cover same as well as prevent the seams formed from 5 opening.

I claim:—

A wall board of the character described, comprising a body portion of suitable material, of reduced cross-section along the edges 10 and provided with a continuous covering material over the front, said edges and a

portion of the back, further covering material over the free space of the back, and strips of material extending for an appreciable distance upon both sides of the 15 seams formed thereby on the back and in one direction substantially to the corresponding edge of the board.

Signed at New York, in the county of New York and State of New York, this 21 20 day of September, A. D. 1921.

JOHN COMERMA.
